UNITED STATES PATENT OFFICE.

SABINA W. COOK, OF DAYTON, WASHINGTON TERRITORY.

WASHING-MACHINE.

SPECIFICATION forming part of Letters Patent No. 355,061, dated December 28, 1886.

Application filed March 31, 1886. Serial No. 197,310. (No model.)

To all whom it may concern:

Be it known that I, SABINA W. COOK, of Dayton, in the county of Columbia, Washington Territory, have invented a new and useful 5 Improvement in Washing-Machines, of which the following is a specification, reference being had to the annexed drawings, forming a part thereof, in which—

Figure 1 is a longitudinal section of my improved washing-machine. Fig. 2 is a transverse section taken on line *y y* in Fig. 1. Fig. 3 is a transverse section taken on line *x x* in Fig. 1.

Similar letters of reference indicate corresponding parts in the different figures of the drawings.

My invention is an improvement in the class of clothes-washers generally denominated "atmospheric pounders."

The feature of novelty is the application to the tube, constituting the body of the pounder, of a funnel which is inserted therein, and contains a loose disk-valve, and has fixed apertured partitions between which said valve is held and free to vibrate to alternately allow and prevent passage of air, as hereinafter described.

My invention consists in a tube connected at one end with an inverted funnel, and provided with a flaring mouth at the opposite end, in which is received an air-valve, which allows air to enter the tube and funnel, but prevents it from escaping therefrom.

The lower end of the tube A is connected 35 with the funnel B, and the upper end of the tube A is provided with a flaring mouth, C, and with a looped handle, D, attached to the side of the flaring mouth and to the side of the tube. In the upper end of the tube is inserted 40 the nozzle *a* of the funnel E. At the juncture of the nozzle *a* and the funnel E is secured the valve-seat *b*, having a central opening, *c*. Below the valve-seat in the nozzle *a* is a fixed "spider" or piece in the form of a Maltese

cross, (shown in plan view, Fig. 2,) and which 45 serves to support the valve normally a short distance below the valve seat *b*.

The valve *e* is preferably made of sheet rubber or other soft material, which will adapt itself automatically to the valve-seat and close 50 the opening *c* whenever air-pressure is created in the funnel B and tube A.

My improved washing-machine is used by pressing the funnel B downward upon the clothes submerged in the water, thus forcing 55 some of the air contained by the funnel, together with the water, through the clothes, the air being prevented from escaping from the top of the tube A by the valve *e*. When the tube A and funnel B are raised, air enters through the 60 opening *c* and around the valve *e*, thus preventing the funnel B from drawing the dirty water back through the clothes. When the funnel is again pressed down upon the clothes, a fresh supply of water and air is forced 65 through the clothes, carrying out more dirt. Each time the funnel B is pushed down upon the clothes it carries a fresh supply of air and water through the clothes, and when it is raised no vacuum is produced, and as a consequence 70 the dirty water forced out by the downward movement of the funnel is not drawn back by its upward movement.

Having thus described my invention, what I claim as new, and desire to secure by Letters 75 Patent, is—

In an atmospheric clothes-pounder, the combination, with the tube A, having flaring or funnel-shaped ends, and the lateral handle D, of the funnel E, inserted in the mouth of said tube and having the centrally-apertured partition *b*, the cross-piece *d*, and the loose intermediate disk-valve, *e*, all as shown and described.

SABINA W. COOK.
